CLAIM

The ornamental design for a sit up bar, as shown and described.

DESCRIPTION

FIG. 1 is a front, top, and right side perspective view of the first embodiment of a sit up bar, showing my new design; FIG. 2 is a rear, top, and left side perspective view of FIG. 1;

FIG. 3 is a front elevation view of FIG. 1;

FIG. 4 is a rear elevation view of FIG. 1;

FIG. 5 is a left side elevation view of FIG. 1;

FIG. 6 is a right elevation view of FIG. 1;

FIG. 7 is a top plan view of FIG. 1;

FIG. 8 is a bottom plan view of FIG. 1;

FIG. 9 is a front, top, and right side perspective view of the second embodiment of a sit up bar, showing my new design; FIG. 10 is a rear, top, and left side perspective view of FIG. 9;

FIG. 11 is a front elevation view of FIG. 9;

FIG. 12 is a rear elevation view of FIG. 9;

FIG. 13 is a left side elevation view of FIG. 9;

FIG. 14 is a right elevation view of FIG. 9;

FIG. 15 is a top plan view of FIG. 9;

FIG. 16 is a bottom plan view of FIG. 9;

FIG. 17 is a front, top, and right side perspective view of the third embodiment of a sit up bar, showing my new design; FIG. 18 is a rear, top, and left side perspective view of FIG. 17;

FIG. 19 is a front elevation view of FIG. 17;

FIG. 20 is a rear elevation view of FIG. 17;

FIG. 21 is a left side elevation view of FIG. 17;

FIG. 22 is a right elevation view of FIG. 17;

FIG. 23 is a top plan view of FIG. 17;

FIG. 24 is a bottom plan view of FIG. 17;

FIG. 25 is a front, top, and left side perspective view of the fourth embodiment of a sit up bar, showing my new design; FIG. 26 is a rear, top, and left side perspective view of FIG. 25;

FIG. 27 is a front elevation view of FIG. 25;

FIG. 28 is a rear elevation view of FIG. 25;

FIG. 29 is a left side elevation view of FIG. 25;

FIG. 30 is a right elevation view of FIG. 25;

FIG. 31 is a top plan view of FIG. 25; and,

FIG. 32 is a bottom plan view of FIG. 25.
